Primary Examiner — Mary Ann Calabrese(74) *Attorney, Agent, or Firm* — Morgan, Lewis & Bockius LLP**(57) CLAIM**

An ornamental design for a combined display and vehicle, as shown and described.

DESCRIPTION

FIG. 1 is a back perspective view of my new design of a combined display and vehicle.

FIG. 2 is a side view of my new design; and,

FIG. 3 is a back view of my new design.

The broken lines showing elements of the combined display and vehicle in the above described figures are for illustrative purposes only and form no part of the claimed design.
